UNITED STATES PATENT OFFICE

2,192,442

INTERNAL COMBUSTION ENGINE

Samuel K. Hoffman, Williamsport, Pa., assignor,
by mesne assignments, to Aviation Manufacturing Corporation, Chicago, Ill., a corporation
of Delaware

Application November 5, 1934, Serial No. 751,491

2 Claims. (Cl. 123—195)

The invention relates to internal combustion engines.

Considerable difficulty is experienced in starting internal combustion engines of high horse power when they are cold, on account of the high viscosity of the lubricating oil left on the cold parts and the difficulty in vaporizing the fuel.

One object of the invention is to provide an internal combustion engine with auxiliary equipment which includes a lubricant pump and an impeller for the coolant which, in starting, are adapted to be operated independently of the crank-shaft and pistons and other operating parts of the auxiliary equipment, so that the lubricant and fluid which is normally used for cooling may be pre-heated to circulate heated fluid to increase the temperature of the working parts of the engine and aid combustion and heated oil to reduce friction in the working parts preparatory to, and for facilitating the starting of the engine.

Other objects of the invention will appear from the detailed description.

The invention consists in the several novel features hereinafter set forth and more particularly defined by claims at the conclusion hereof.

In the drawings:

Fig. 1 is a longitudinal section of a portion of an internal combustion engine having the invention applied thereto. Fig. 2 is a transverse section taken on line 2—2 of Fig. 1. Fig. 3 is a section on an enlarged scale taken on line 3—3 of Fig. 2, illustrating the reversible shaft between the engine and the auxiliary assembly and the over-running clutch for driving the lubricant pump and impeller for cooling fluid and the driving mechanism therefor. Fig. 4 is an elevation of the reversible drive-shaft for the auxiliary equipment positioned so it will drive the auxiliary equipment in the same direction as shown in Fig. 3 from an oppositely rotating engine.

The invention is exemplified in an engine comprising a casing or crank-case 20; a crank-shaft 23 which is journaled in the crank-case at 20^a and such other usual elements of an internal combustion engine, all of which may be of any suitable construction, as well understood in the art.

The auxiliary equipment of the engine comprises a rotary pump B for supercharging the engine; an electric starter C connectable to initially drive the crank-shaft; a rotary pump D for forcing the air or cooling fluid to the cooling means for the engine; a fuel-charging pump E

and a pump G for circulating lubricant through the lubricating system of the engine, all of which are of the uni-directional rotary type or connected to the engine so that each will function by rotation in a single direction. The crank-case is formed of vertically divided sections. The auxiliary equipment is driven from one end of the crank-shaft 23. The driving mechanism for the auxiliary equipment is carried in a rearward extension 26 of the crank-case 20 and a sectional casing or housing which is carried by the engine-case and comprises a head 24 and a housing 27, both of which are removably secured to the rear end of the extension 26.

The mechanism for driving the auxiliary equipment comprises a hollow shaft 28 which is reversible from end to end and is provided with splines 30 adjacent, but spaced from, one of its ends and splines 30^a at its other end; an axially extending socket 29 in the outer end of the crank-shaft 23 which is provided with elongated splines 29^a which are adapted to interfit with either of the splines 30, 30^a according to the position of the shaft 28; a bevel-gear 33 which is provided with an integral hollow shaft 31 carried in a ball-bearing 32 and with a hub 34 which is journaled in the spider 35, and is provided with splines 37 which are adapted to be driven by splines 30^a on shaft 28; a mating bevel-gear 36 which is coaxial with gear 33 and provided with a hub which is journaled in spider 35; and a set of intermediate gears 40, 41, 42, which mesh constantly with both of the gears 33, 36. Gears 40, 41, 42 transmit power between gears 33, 36 and are, respectively, adapted to drive in the same direction the elements of the uni-directional auxiliary equipment from a crank-shaft which is driven either in one or the opposite direction.

Shaft 28 is reversible from end to end to drive either of the rotatable gears 33, 36, which are driven in relatively opposite directions through gears 40, 41 and 42, in the same direction as the crank-shaft or engine. For this purpose, when shaft 28 is in one position (Fig. 3), splines 30 on shaft 28 interfit with the splines 29^a and splines 30^a on shaft 28 interfit with splines 37 on gear 33 and drive the gear 33 in the same direction as the crank-shaft when shaft 28 is in one of its alternative positions. In the reversed position (Fig. 4) of shaft 28, splines 30^a will interfit with the inner ends of the splines 29^a in the crank-shaft and splines 30 on shaft 28 will interfit with splines 37 on gear 36 and drive the gear 36 in the same direction as the crank-shaft 23. The rotary auxiliary equipment is usually adapted for

operation in one direction only. When the shaft 28 is coupled, for example, to the crank-shaft of an engine with right-hand rotation, and to gear 33, as shown in Fig. 3, gear 33 will drive the gears 40, 41, 42 in the correct direction for operating the rotary auxiliary equipment. When the equipment is to be used with an engine or crank-shaft with left-hand rotation, the shaft 28 is reversed (Fig. 4) to position splines 30^a on shaft 28 where they will interfit with the inner ends of splines 29^a and splines 30 on shaft 28 will interfit with the splines 37' on gear 26. As a result, gear 36 will be driven in the same direction as the crank-shaft and the auxiliary equipment will be driven in the same direction as it is driven by gear 33 when the latter is operated from an oppositely rotating engine. This feature adapts the auxiliary equipment for selective functioning with either a left or right-hand engine. The axes of the three beveled intermediate gears 40, 41 and 42 are radial from the axis of the gears 33, 36 to provide compact mechanism for driving the auxiliary equipment.

Beveled intermediate gear 40 is provided with an integral shaft 43 which is mounted in a sectional head 44 which is removably secured in the extension 26 of the crank-case 20 and is adapted to be driven by an electric starter C which may be of any suitable construction. A ratchet clutch 46 is provided on the outer end of shaft 43 and is adapted to be driven by co-axial clutch wheel 47 on the starter. Clutch wheel 47 is adapted to be automatically coupled with clutch wheel 46 when the starter is operated to start the motor, as well understood in the art.

When reversible shaft 28 is connected to drive gear 33, the starter, through gear 40, will drive the crank-shaft in one direction, and when shaft 28 is coupled to gear 36, the direction of rotation of the crank-shaft by gear 40 will be in the opposite direction. As a result, the starter mechanism is adapted to drive the crank-shaft to start the engine according to the selected direction of rotation of the engine and by the reversal of shaft 28.

Beveled intermediate gear 41, which meshes with beveled gears 33, 36, is mounted in a sectional head 48 which is removably secured in housing-member 27 and is provided with an integral shaft 50. A pinion 51 is splined to the outer end of shaft 50 and meshes with an internal gear 52 on the shaft 53 of the fuel-charging pump E which is removably secured against the outer end of the head 48 and with said head to housing-member 27. The fuel-charging pump 54 is of the rotary type and may be of any suitable construction, as well understood in the art.

Beveled gear 42, which also meshes with oppositely rotating, beveled gears 33, 36, has an integral shaft 58, which is journaled in a sectional head 59, which is mounted in the cylindrical member 60 of the casing extension 26. Shaft 58 is connected to drive a co-axial shaft 61 also mounted in head 59 through an over-running or one-way spring clutch 62 mounted in cylindrical recesses in the contiguous ends of said shafts, so as to permit shaft 61 to be driven in one direction independently of the shaft 58, intermediate gears 40, 41, 42 and the gears 33, 36.

70 A shaft 63 for operating the coolant pump D and co-axial with shafts 61 and 58, is journaled in a head 64 which is removably secured to a member of the case-extension 26, and has its upper end splined to shaft 61. The pump D comprises 75 a casing 65, consisting of a member integrally

formed with the head 64, a cover 65^a, and a rotor or impeller d for circulating fluid through the cooling means of the engine fixed to the lower end of shaft 63, which extends into casing 65. The casing has a depending inlet duct 66 and outlet duct 67 for delivering cooling fluid to the engine, wherever desired. Since gear 42, which drives the impeller for the cooling fluid, is alternately driven by gears 33, 36, when the engine is rotating in opposite directions, the impeller 10 will always be driven in the same direction and function to deliver the cooling fluid to the engine. Shaft 63 is sealed by packings 68, glands 69, and a spring 70 interposed between the glands.

A gear 71 is formed on the hollow shaft 61 15 which is driven by the over-running or one-way clutch 62 and serves to drive the lubricant pump G. Gear 71 meshes with an idler gear 72 which is mounted on a stud 73 which is carried by a head g which is removably secured to the bottom of the casing-extension 26, which contains an oil sump from which lubricant can flow to pump G. Idler gear 72 meshes with a gear 74 which is fixed to the drive-shaft 75 of the pump G which is illustrated as the three-stage type, each stage comprising a pair of intermeshing gears 77, 78. Two of the stages may be connected to scavenge the lubricating oil from the crank-case and one may be used to supply lubricating oil under pressure to the lubricating system of the engine. The case g' of pump G is removably mounted on the head g which is secured to the casing-extension 26. Since the lubricating pump G is driven from beveled gear 42 through shafts 58, 61, gears 71, 72, 74, and gear 42 is driven in the same direction while the engine is driven in either direction, through the selective adjustment of shaft 28, the gear-pump G will be driven in the same direction at all times, to function with the engine while it is driven in either direction or with a right or a left-hand engine.

A hollow shaft 111 is journaled in a head 112 which is removably secured in the housing-member 27 and carries at its inner end an integral beveled gear 113 which meshes with a beveled gear 114 integral with the shaft 61 which is driven through the over-running spring clutch 62. The outer end of shaft 111 is provided with a splined socket 115 to adapt it to receive the shaft of a small electric motor x which is illustrated in Fig. 2 as detached from the assembly. The purpose of the over-running clutch 62 and this shaft 111 is to permit the impeller for the cooling fluid and the lubricant pumps, which are also driven by shaft 61, to be operated independently of the engine and the other auxiliary equipment.

Starting the engine in cold weather is sometimes difficult and, by supplying pre-heated liquid to the cooling means for the engine from impeller D and pre-heated lubricant to the lubricant-circulating system of the engine, the temperature of the working parts of the engine will be increased and facilitate the starting of the engine.

When this is desired the shaft of a small portable electric motor (not shown), or a shaft from any other source of power, can be coupled to the outer end of shaft 111 to drive the shaft 61 through gears 113, 114 in the direction for normal operation. The spring-clutch 62 will permit the shaft 61 to rotate in its designed direction while the shaft 58, which is normally driven from the engine, remains idle. This operation of shaft 111 will operate the impeller D through shafts 61 and 63 and will operate the lubricant pump G 75

through gears 71, 72, 74. In this operation, any suitable means, such as an electric heater, may be used to heat the lubricant in the pump to cause it to circulate heated oil through the lubricating system of the engine. This exemplifies means for driving, from an outside source, for starting purposes, the impeller D for the coolant and the lubricant pump G, independently of the engine and the other auxiliary equipment driven by gears 33, 40 and 41, which are normally operated by the engine. By reason of the reversibility of shaft 28, this mechanism is normally operable from a right or left-hand engine.

The rotary pump B for forcing air to super-charge the motor comprises a casing b which is secured to the back of a housing-member 21 which is fixed to the rear end of the crank-case extension 26, and a rotor or impeller 81 with blades 82 for drawing air from a valve-controlled intake 83 and propelling it from the casing b into the manifold b' which delivers the air to the intakes of the engine cylinders, as well understood in the art. Rotor 81 is driven from beveled gear 33 so that it will always be driven in the same direction while the crank-shaft of the motor is rotated in either direction.

The driving mechanism for the impeller B comprises a gear 85 which is splined to the hub of gear 33; a set of three pinions 86 which mesh with gear 85; a set of three helical gears 93 mounted on shafts 87; a hydraulic drive H between each of the pinions 86 and gear 93; and a helically toothed pinion 94 which meshes with the gears 93 and is integrally formed with the shaft 95 to which the impeller 81 is splined.

Since the super-charger is driven from beveled gear 33 through the gearing last described, it will always be driven in the same direction while the engine is rotated in opposite direction.

40 A shaft 106, co-axial with the crank-shaft and shaft 28, is splined at 107 to the shaft 31 of gear 33. This shaft extends outwardly through the hollow shaft 95 which carries and drives the impeller head 81 and has its outer end journaled in a bearing 108 carried by the casing 79 of the super-charger. The outer end of this shaft has a splined socket 109 which is adapted to receive a shaft for any additional auxiliary mechanism desired. A cap 110 is secured to enclose the end of shaft 106 when it is not in use.

50 In operation, the engine drives the entire auxiliary equipment through shaft 28. If the engine is set to operate, or is operative in one direction, the shaft 28 will be placed in the position to engage the gear 33 by means of splines 31. The entire auxiliary equipment will then be driven in the proper direction for which it is designed. When the engine is set so as to be, or is operated in the reverse direction, the shaft 28 will be reversed so that its spline 30 will drive the gear 36 which, through gears 40, 41, 42, rotates in the opposite direction to gear 33. By connecting the shaft 28 to drive the oppositely rotating gear

36, with the oppositely running crank-shaft, the entire auxiliary equipment will function in its proper direction, notwithstanding the change in direction of rotation of the engine.

When difficulty is encountered in starting the 5 engine, the pump D and lubricant pump G will be operated from an outside source through shaft 111, as hereinbefore described.

The invention exemplifies means whereby the impeller for coolant may be driven from an outside source and independently of the crank-shaft and other auxiliary equipment, so that heated fluid can be circulated around the engine to increase the temperature and aid combustion preparatory to starting the engine. Also means 10 whereby the lubricant pump may be operated from an outside source of power, independently of the crank-shaft, to circulate heated oil through the lubricating system of the engine to reduce friction of the working parts in starting the engine. Also, independently operable auxiliary equipment for these purposes which is adapted to be normally driven from an engine rotating either in a right or left-hand direction.

The invention is not to be understood as restricted to the details set forth since these may be modified within the scope of the appended claims without departing from the spirit and scope of the invention.

What I claim as new and desire to secure by Letters Patent is:

1. In an auxiliary assembly adapted for use with an engine, the combination of a unidirectional rotary device for forcing a fluid to the engine, a shaft adapted to be connected to and driven by the engine, an automatically-acting one-way clutch comprising a clutch-spring and a pair of coaxial shafts into both of which the spring is extended, one of said hollow shafts being connected to be driven by the engine-driven shaft and the other of which is connected to drive the device, a transversely extending shaft, gears between the transversely extending shaft and the hollow shaft connected to drive the device, and means for coupling an auxiliary motor to the outer end of the transversely extending shaft.

2. In an auxiliary assembly adapted for use with an engine, the combination of a plurality of uni-directional rotary devices for forcing different fluids to the engine, a shaft adapted to be connected to and driven by the engine, an automatically-acting one-way clutch comprising a clutch-spring and a pair of coaxial shafts into both of which the spring is extended, one of said hollow shafts being connected to be driven by the engine-driven shaft and the other of which is connected to drive both of said devices, a transversely extending shaft, gears between the transversely extending shaft and the hollow shaft connected to drive the devices, and means for coupling an auxiliary motor to the outer end of the transversely extending shaft.

SAMUEL K. HOFFMAN.
